United States Patent Office

Des. 200,896
Patented Apr. 20, 1965

200,896

WALL MOUNTED HAND DRIER

Robert L. Gallup, Niles, Mich., assignor to Utah-American Corporation, Huntington, Ind., a corporation of Indiana

Filed June 11, 1964, Ser. No. 80,359

Term of patent 14 years

(Cl. D4—3)

Fig. 1.

Fig. 2.

Fig. 3.

Fig. 4.

FIG. 1 is a front perspective view of a wall mounted hand drier showing my new design.

FIG. 2 is a side view taken from the left-hand side of the drier.

FIG. 3 is a bottom view of the drier.

FIG. 4 is a rear view of the drier.

The dominant features of the design reside in the portions shown in full lines. The right side is a mirror image of the left side shown.

I claim:

The ornamental design for a wall mounted hand drier, as shown and described.
